UNITED STATES PATENT OFFICE

JESSE D. LANGDON, OF LOS ANGELES, CALIFORNIA

PUMP UNIT

Application filed March 24, 1928. Serial No. 264,296.

The invention relates to improvements in pumps particularly for use in dispensing fluid where an accurate measure is desired, and the objects of the improvement are:

5 First, to provide a piston having a circumferential tension against a cylinder at all times without the use of the usual piston rings.

Second, to provide a novel piston with a 10 check valve.

Third, the provision of means to eliminate the by-passing of fluid around a piston rod used in connection with a rack and pinion pump.

15 Fourth, the provision of convenient and economical assembly of the component of the pump.

Other and further objects will appear as the description matter proceeds, as illus- 20 trated by the drawing herewith, in which,

The figure is a vertical section of one form of the pump. —1— is a crank to which is attached a pinion —2— which meshes with a rack —3— connected by a piston rod —4— 25 to a valve cage —5—, threaded on a bushing —6— constituting the clamping means to hold two piston cups —7— in proper relationship to form the piston —8—. A ball —9— is encased in the cage, and is limited in 30 its upward movement by a pin —19— extending through said cage, and the cage has openings —18— therein for the flow of the fluid.

35 A packing tube —11— is disposed within the cylinder and has its upper end threaded into the head —12— which is threaded on the upper end of the cylinder, and a cap —10— is threaded on the lower end of said tube —11—. The piston rod is slidable through 40 said cap to be guided thereby, and said cap has a packing gland —20— to prevent leakage. The tube —11— is used to prevent the leakage of fluid around the piston rod through the cylinder head —12—.

45 The cylinder head —12— has an outlet spout —14— on which a ball check valve —15— is seatable. Said check valve is limited in its unseating movement by a pin —17— extending across the discharge nozzle 50 —16—.

The operation of my invention is substantially as follows: The crank —1— is turned to operate the pinion —2— and rack —3— for actuating the piston rod —4— to exert pulling or pushing action on cage —5— and piston —8— up or down during the pumping movement. When the piston —8— is forced downwardly the check valve —9— is raised by the suction created within cylinder —13—, thus drawing the fluid into the same. 55 When the piston is actuated in the opposite direction, or upwardly, check valve —9— is immediately closed.

The check valve —9— closes instantly by its own weight without the movement of the piston —8— within the cylinder —13—. As the piston travels upwardly the check valve —15— is moved upwardly by the fluid which is forced from the cylinder —13— through the outlet nozzle —16—. The check valve 70 —15— is immediately closed by gravity whenever the operation of the pump ceases.

The piston cups —7— are formed preferably of two stampings with the peripheral edge tapered to a feather edge. The cups —7— are preferably of brass or copper, or a softer metal in relation to a cylinder of harder metal such as steel or iron, into which said cups are forced under compression. The piston cups —7— being .005 larger than 75 the diameter of the cylinder —13—, and being of flexible material and form, the peripheral edges are constantly expanded by fluid pressure against the inside of each cup during their operation within the cylinder. 80

Having described my invention and the 85 operation thereof, I claim:

A piston comprising a pair of soft metal cups disposed back to back and having rims extending away from one another to be compressed within a cylinder, a bushing extending through said cups, a valve cage threaded on said bushing and clamping said cups, and a valve seatable on said bushing within said cage. 90

In testimony whereof, I have signed my name to this specification.

JESSE D. LANGDON.
